MULTIPLE TUBE, CONVERGENT LINE OSCILLATOR

Robert M. Page, Washington, D. C.

Application November 20, 1942, Serial No. 466,292

4 Claims. (Cl. 250—36)

(Granted under the act of March 3, 1883, as amended April 30, 1928; 370 O. G. 757)

1

This invention relates to the generation of super-frequency energy at high power levels.

It is frequently desirable to produce power at these frequencies at levels which are unobtainable from one or two tubes. However, when more than two tubes are employed for this purpose many difficulties are encountered.

For example, it is not feasible to increase power at these frequencies by adding tubes in parallel since the tube impedance is too low and inter-electrode capacity is too high. It is necessary to avoid circuits which require matching of tubes by special selection. The oscillator should also respond faithfully to modulation potentials as does a one or two-tube oscillator. Space and weight considerations sometimes are likewise of high importance.

It is among the several objects of the invention to provide a light and compact multiple tube single-phase oscillator having short leads, which will faithfully respond to modulation potentials and the tubes of which need not be matched by special selection.

Other objects will become apparent from a careful consideration of the following description, when taken together with the accompanying drawings, in which:

Fig. 1 is a schematic circuit diagram of an oscillator embodying the invention, and

Fig. 2 is a schematic circuit diagram of another embodiment of the invention.

Figs. 3 and 4 show in partial perspective, the embodiments illustrated respectively in Figs. 1 and 2.

In Figs. 1 and 3 are shown four tubes 10, 11, 12 and 13 having their grids connected to a common point 14 by means of a four-wire convergent frame. The plates are connected to a common point 15 through a similar convergent frame. Each side of the filaments is connected to a separate two-wire convergent frame, the two frames being inductively coupled and the filaments of each oppositely located pair of tubes being connected in parallel to correspondingly located wires of the frames. Thus, leads 18 and 20 connect corresponding sides of the filaments of tubes 10 and 12 and tubes 11 and 13 respectively to the wires 22 and 23 comprising one convergent frame and leads 19 and 21 connect the opposite sides of the filaments of the same respective tubes to the two wires 24 and 25 comprising the other frame. The wires 22 and 25 extend in mutual parallelism, as likewise do wires 23 and 24. The filament frames should be approximately a quarter-wave length long and are tuned by means of

variable self inductance to resonate at the desired frequency. The filament frame of tube 10 is connected to the filament frame of tube 11 and the filament frame of tube 12 is connected to the filament frame of tube 13.

Fig. 4 shows a variation of the embodiment of Fig. 3 in which the filament frames of the tubes are connected to a common point.

Fig. 5 shows a variation of the embodiment of Fig. 3 in which the filament frames of the tubes are connected to a common point.

Fig. 6 shows a variation of the embodiment of Fig. 3 in which the filament frames of the tubes are connected to a common point.

Fig. 7 shows a variation of the embodiment of Fig. 3 in which the filament frames of the tubes are connected to a common point.

Fig. 8 shows a variation of the embodiment of Fig. 3 in which the filament frames of the tubes are connected to a common point.

Fig. 9 shows a variation of the embodiment of Fig. 3 in which the filament frames of the tubes are connected to a common point.

Fig. 10 shows a variation of the embodiment of Fig. 3 in which the filament frames of the tubes are connected to a common point.

Fig. 11 shows a variation of the embodiment of Fig. 3 in which the filament frames of the tubes are connected to a common point.

Fig. 12 shows a variation of the embodiment of Fig. 3 in which the filament frames of the tubes are connected to a common point.

Fig. 13 shows a variation of the embodiment of Fig. 3 in which the filament frames of the tubes are connected to a common point.

Fig. 14 shows a variation of the embodiment of Fig. 3 in which the filament frames of the tubes are connected to a common point.

Fig. 15 shows a variation of the embodiment of Fig. 3 in which the filament frames of the tubes are connected to a common point.

Fig. 16 shows a variation of the embodiment of Fig. 3 in which the filament frames of the tubes are connected to a common point.

Fig. 17 shows a variation of the embodiment of Fig. 3 in which the filament frames of the tubes are connected to a common point.

Fig. 18 shows a variation of the embodiment of Fig. 3 in which the filament frames of the tubes are connected to a common point.

Fig. 19 shows a variation of the embodiment of Fig. 3 in which the filament frames of the tubes are connected to a common point.

Fig. 20 shows a variation of the embodiment of Fig. 3 in which the filament frames of the tubes are connected to a common point.

Fig. 21 shows a variation of the embodiment of Fig. 3 in which the filament frames of the tubes are connected to a common point.

Fig. 22 shows a variation of the embodiment of Fig. 3 in which the filament frames of the tubes are connected to a common point.

Fig. 23 shows a variation of the embodiment of Fig. 3 in which the filament frames of the tubes are connected to a common point.

Fig. 24 shows a variation of the embodiment of Fig. 3 in which the filament frames of the tubes are connected to a common point.

Fig. 25 shows a variation of the embodiment of Fig. 3 in which the filament frames of the tubes are connected to a common point.

Fig. 26 shows a variation of the embodiment of Fig. 3 in which the filament frames of the tubes are connected to a common point.

Fig. 27 shows a variation of the embodiment of Fig. 3 in which the filament frames of the tubes are connected to a common point.

Both embodiments of the invention show a

marked absence of radiation from the oscillator itself. This is in direct contrast to the large radio frequency fields to be found in the vicinity of conventional oscillators.

It should be noted that an oscillator constructed in accordance with the invention requires an even number of tubes for its proper functioning.

Although only two embodiments of the present invention have been shown and described in detail heretofore, it is to be expressly understood that various changes and substitutions may be made therein without departing from the spirit of the invention as well understood by those skilled in the art. Reference therefore will be had to the appended claims as a definition of the limits of the invention.

The invention described herein may be manufactured and used by or for the Government of the United States of America for governmental purposes without the payment of any royalties thereon or therefor.

I claim:

1. An oscillation generator comprising an even number of electron discharge devices intersected by a plane and symmetrically disposed with regard to a point in said plane, each of said devices comprising an anode, a control grid and an electron-emitting electrode, an anode frame for said devices comprising separate, equal length, converging conductors connecting said anodes together in a common point outside the plane of said devices, and a grid frame for said devices comprising separate, equal length, converging conductors, connecting said grids together in a common point also outside of the plane of said devices.

2. An oscillation generator comprising an even number of electron discharge devices intersected by a plane and symmetrically disposed with regard to a point therein, each of said devices comprising a plate, a control grid and an electron-emitting electrode, a pyramidal convergent wire frame connecting said control grids together in a common point outside the plane of said devices, a similar pyramidal convergent wire frame connecting said plates together in a common point outside the plane of said devices, and a pair of convergent wire frames each connecting together one side of the electron-emitting electrodes of said devices.

3. An oscillation generator comprising an even number of electron discharge devices intersected by a plane and symmetrically positioned with regard to a point in said plane, each of said devices comprising a filament, a control grid and an

anode, a convergent line frame connecting said control grids and comprising a conductor devoid of lumped reactance leading from each of said grids to a common point outside of said plane, a similar frame connecting said anodes together in a common point outside the plane of said devices, said anode frame being positioned to surround the grid frame, means including a first quarter wave two wire convergent line frame connecting one side of the filaments of said devices together, and means including a second quarter wave two wire convergent line frame connecting the other side of the filaments of said devices together, said first and second filament convergent line frames being so positioned as to be inductively coupled.

4. An oscillation generator comprising an even number of electron discharge devices intersected by a plane and symmetrically positioned with regard to a point in said plane, each of said devices comprising a filament, a control grid and an anode, a convergent line frame connecting said control grids and comprising a conductor devoid of lumped reactance leading from each of said grids to a common point outside of said plane, a similar frame connecting said anodes together in a common point outside the plane of said devices, said anode frame being positioned to surround the grid frame, means including a first quarter wave two wire convergent line frame connecting one side of the filaments of said devices together, and means including a second quarter wave two wire convergent line frame connecting the other side of the filaments of said devices together, said first and second filament convergent line frames being so positioned as to be inductively coupled and means for tuning said filament frames.
